SHELTER

Frederick Kraissl, Jr., 244 Kinderkamack Road,
North Hackensack, N.J.

Filed Jan. 22, 1962, Ser. No. 68,397

Term of patent 14 years

(Cl. D13—1)

FIG. 1.

FIG. 2.

FIG. 3.

FIG. 4.

I claim:

The ornamental design for a shelter, as shown.
